UNITED STATES PATENT OFFICE.

MANSIR A. HALL, OF NORTH HARTFORD, NEW YORK.

DESIGN FOR A POTATO-HOOK.

SPECIFICATION forming part of Design No. 34,762, dated July 9, 1901.

Application filed May 23, 1901. Serial No. 61,619. Term of patent 14 years.

To all whom it may concern:

Be it known that I, MANSIR A. HALL, a citizen of the United States, residing at North Hartford, in the county of Washington and State of New York, have invented and produced a new and original Design for a Potato-Hook, of which the following is a specification.

My invention relates to a new and original design for a potato-hook and is illustrated in the accompanying drawings, in which—

Figure 1 is a perspective view of the hook. Fig. 2 is a section along xx , Fig. 1. Fig. 3 is a section along yy , Fig. 1.

The invention consists in the design for a potato-hook substantially as shown in the drawings, in which the numeral 1 indicates the head part of the potato-hook, and 2 the tines. The tines along the section-line x are narrow as compared with the portions thereof nearer the point or free end, (indicated by sec-

tion-line y .) At such narrowed portions the tines are rounded at their sides, or are what might be in a general way called "oval" or "ovoid" shape, as seen in Fig. 2, while along the line y the tine is flattened or more of triangular shape. A rib or central ridge runs along the front of each tine or tooth.

The design presents a potato-hook having a novel, pleasing, and distinctive appearance.

What I claim as new, and desire to secure by Letters Patent, is—

The design for a potato-hook substantially as herein shown and described.

In testimony whereof I have hereunto set my hand in the presence of two subscribing witnesses.

MANSIR A. HALL.
